FRANK THORNTON, JR., OF PITTSBURGH, AND EMERSON S. ZUCK, OF WILKINSBURG, PENNSYLVANIA, ASSIGNORS TO WESTINGHOUSE ELECTRIC AND MANUFACTURING COMPANY, A CORPORATION OF PENNSYLVANIA.

ELECTRIC-ARC-WELDING SYSTEM.

1,296,020.

Specification of Letters Patent.

Patented Mar. 4, 1919.

Application filed April 1, 1915. Serial No. 18,504.

To all whom it may concern:

Be it known that we, FRANK THORNTON, Jr., a citizen of the United States, and a resident of Pittsburgh, in the county of Allegheny and State of Pennsylvania, and EMERSON S. ZUCK, a citizen of the United States, and a resident of Wilkinsburg, in the county of Allegheny and State of Pennsylvania, have invented a new and useful Improvement in Electric-Arc-Welding Systems, of which the following is a specification.

Our invention relates to electric arc welding systems, and it has for its object to provide an arc welding system which shall be simple in arrangement and efficient in operation and which shall be provided with means for automatically adjusting the circuit conditions without attention on the part of the operator.

The single figure of the accompanying drawing is a diagrammatic view showing a welding system constructed in accordance with our invention.

In electric arc welding, it often happens that the working electrodes, especially metal electrodes, become fused or "frozen" to the work, resulting in a dead short circuit and a rush of current that is limited only by the resistance of the welding circuit. In order to restrain such rushes of current, a resistance element is sometimes placed permanently in series with the arc circuit in addition to the usual steadyng resistors required by the arc. Such extra resistance elements are expensive and consume a great deal of power.

According to our present invention, we provide means for interrupting the welding circuit when the current becomes excessive by reason of the working electrode being maintained in contact with or "frozen" to the work, and we further provide automatic means for reestablishing the circuit and restoring it to operating condition after the electrodes have been separated and the short circuit consequently removed. By these combined means, the electrical condition of the circuit is automatically regulated without any attention on the part of the operator, and dangerous current rushes are effectually prevented.

In the system shown in the accompanying drawing, a welding electrode 1 is shown in

cooperative relation to a metallic object 2 which diagrammatically represents the work to be welded. The electrode 1 receives current from any suitable source through a conductor 3, and the work 2 is connected to the source of power through a conductor 4. A set of steadyng resistors 5 is inserted in series in the conductor 3. The parts thus far described constitute an ordinary arc-welding circuit.

The conductor 3 is interrupted at 6 and is adapted to be completed at this point of interruption by means of a bridging piece 7 carried by the core of a magnet switch 8. A resistor 9 is connected to the conductor 3 at points 10 and 11 and is adapted to be inserted in series in the conductor 3 when the conductor is interrupted at 6.

The magnet switch 8 is operated by means of a solenoid core 12 energized by a conductor 13, which is connected to the conductor 3 at a point 14 and is interrupted at 15, the terminals 16 and 17 at this point being normally connected by a bridge piece 18 that is carried by the core of an overload relay 19. The relay core 19 is operated by means of a coil 20 that is inserted in series in the conductor 3.

The core of the magnet switch 8 carries, in addition to the bridge piece 7, a second bridge piece 21 that is adapted to connect terminals 22 and 23 connected respectively to conductors 24 and 25. The conductor 24 is joined to the conductor 4 at the point 26, and the conductor 25 is joined at 27 to a conductor 28 that is connected to the solenoid coil 12 of the magnet switch. A shunt circuit around the terminals 22 and 23 is provided by the conductor 28 and a conductor 29, terminals 30 and 31 of the conductors 28 and 29, respectively, being adapted to be connected by the bridging piece 32 of a relay 33 that is energized by means of a solenoid coil 34 the ends of which are connected to the conductors 3 and 4 at the points 35 and 36, respectively.

The overload relay 19 is so designed that, in the normal operation of the welding circuit, the bridge piece 18 will connect the terminals 16 and 17, and current will therefore flow through the conductor 13 and the coil 12 to maintain the magnet switch 8 in position to close the conductor 3 at 6. In this position of the magnet switch 8, the bridge

piece 21 connects the terminals 22 and 23, and the current from the coil 12 therefore flows to the conductor 4 through conductors 25 and 24.

- 25 and 21.

5 If the welding electrode should become "frozen" to the work, the resulting rush of current will raise the core 19 of the overload relay which, in turn, opens the main circuit at 6, since the core of the magnetic switch

10 8 drops by gravity and remains in its lower position, as shown, as long as its coils are deenergized. The resistance element 9 is inserted in the main circuit by the foregoing operation of the magnet switch 8, and the

15 15 resistance of this element should be great enough to prevent current flow in the main circuit almost entirely. Since the overload no longer exists, the relay 19 is again closed by gravity, but the circuit which energizes

20 20 the magnet switch 8 remains open, since the bridge pieces 21 and 32 are both in their lower positions, as shown, the bridge piece 21 having been carried down by the opening of the magnetic switch 8, while the relay

25 25 33 is inoperative since the small current flowing in the main circuit is shunted around it through the electrodes 1 and 2. When the electrode 1 is broken away from the work 2, a relatively high voltage is impressed upon

30 30 the coil 34 of the relay 33, and the current flowing through this coil raises the relay core and connects the terminals 30 and 31. This operation closes the auxiliary circuit which includes the operating coils of the

35 35 magnet switch 8, thus raising the switch core and closing the main circuit at 6. The welding circuit is now in its normal operating condition, and the operator may again strike the welding arc without operating

40 40 switches or giving the circuit any other attention.

It will be evident from the foregoing description, and from the drawing, that our welding system effectually prevents dangerous surges of current that tend to result from the "freezing" of the welding electrode to the work, and that the removal of the electrode from the work accomplishes the reenergizing of the circuit. Positive current regulation is thereby assured, and much time is saved which would otherwise be consumed in making circuit adjustments. The circuits and apparatus which we have shown and described may be variously modified within the scope of our invention, and it is therefore to be understood that no limitations are to be imposed upon our invention except such as are indicated in the appended claims.

60 We claim as our invention:

- 65 We claim as our invention:

1. An arc welding system comprising welding electrodes, a welding circuit including the said electrodes, means for partially deenergizing the said circuit when the said electrodes are brought into contact, and

other means for automatically reenergizing the said circuit after the said electrodes are separated.

2. An arc welding system comprising welding electrodes, a circuit adapted to supply energy to the said electrodes, means for partially deenergizing the said circuit when the said electrodes are maintained in contact for a substantial period, and other means, operated by the residual current in the said circuit, for automatically reenergizing the said circuit after the said electrodes are separated. . . .

3. An arc welding system comprising welding electrodes, a circuit adapted to supply energy to the said electrodes, a magnetically-operated switch adapted to control the said circuit, an overload relay in the said circuit adapted to operate the said switch when the current in the said circuit exceeds a predetermined value, and means for operating the said switch to restore the said circuit to its normal condition when the said electrodes are separated. 80 85

4. An arc welding system comprising 90
welding electrodes, a circuit adapted to supply
energy to the said electrodes, a resistance
element, means for normally shunting the
current in the said circuit around the said
resistance element and for inserting the said 95
resistance element in series in the said cir-
cuit when the said electrodes are maintained
in contact for a substantial period, and ad-
ditional electro-responsive means for restor-
ing the circuit to its normal condition when 100
the said electrodes are separated.

- the said electrodes are separated.

5. An arc welding system comprising welding electrodes, a main circuit adapted to supply energy to the said electrodes, a magnetically operated switch adapted to control the said circuit, an auxiliary circuit for energizing the said magnetically operated switch, an overload relay adapted to open the said auxiliary circuit when the said electrodes are maintained in contact for a substantial period, and means for closing the said auxiliary circuit when the said electrodes are separated. . .

105 110

6. An arc welding system comprising welding electrodes, a main circuit adapted to supply energy to the said electrodes, a magnetically-operated switch adapted to control the said circuit, an auxiliary circuit for energizing the said magnetically operated switch, an overload relay adapted to open the said auxiliary circuit when the said electrodes are maintained in contact for a substantial period, and a second relay adapted to be energized when the said electrodes are separated and to thereby close the said auxiliary circuit. 115 120 125

7. An arc welding system comprising welding electrodes, a main circuit adapted to supply energy to the said electrodes, a resistance element, a magnetically operated 130

switch adapted, when energized, to shunt the current in the said circuit around the said resistance element, and also adapted, when de-energized, to put the said resistance element in series with the said main circuit, an auxiliary circuit for energizing the said magnetically-operated switch, an overload relay adapted to open the said auxiliary circuit when the said welding electrodes are maintained in contact for a substantial

period, means for maintaining the said auxiliary circuit open as long as the said electrodes are in contact, and electro-responsive means for closing the said auxiliary circuit when the said electrodes are separated. 15

In testimony whereof we have hereunto subscribed our names this 29th day of March, 1915.

FRANK THORNTON, JR.
EMERSON S. ZUCK.
